US00D757697S

(12) **United States Design Patent**
Dubrule et al.

(10) **Patent No.:** **US D757,697 S**
(45) **Date of Patent:** **** May 31, 2016**

(54) **ROUTER**

(71) Applicant: **Cisco Technology, Inc.**, San Jose, CA (US)

(72) Inventors: **Craig Donald Dubrule**, Cary, NC (US); **Mahbubul Alam**, San Jose, CA (US); **Hugo J. W. Vliegen**, Menlo Park, CA (US); **Chandrodaya Prasad**, Santa Clara, CA (US)

(73) Assignee: **Cisco Technology, Inc.**, San Jose, CA (US)

(**) Term: **14 Years**

(21) Appl. No.: **29/521,449**

(22) Filed: **Mar. 24, 2015**

Related U.S. Application Data

(62) Division of application No. 29/416,694, filed on Mar. 26, 2012, now Pat. No. Des. 728,539.

(57) **CLAIM**

The ornamental design for a router, as shown and described.

DESCRIPTION

FIG. 1 is a front perspective view of a router showing our new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a rear elevational view thereof.

The portions illustrated in broken lines form no part of the claimed design.

1 Claim, 5 Drawing Sheets
